UNITED STATES PATENT OFFICE.

HENRY YERBURY HOOPER, OF EAST ORANGE, NEW JERSEY.

RADIATOR CAP FOR AUTOMOBILES.

Application filed August 16, 1922. Serial No. 582,115.

To all whom it may concern:

Be it known that I, HENRY YERBURY HOOPER, a citizen of the United States, residing in East Orange, in the State of New Jersey, have invented certain new and useful Improvements in Radiator Caps for Automobiles, of which the following is a specification, reference being had to the accompanying drawing, forming a part hereof.

10 This invention relates to an improved ornamental radiator cap for automobiles and is designed primarily to meet such conditions as are found in and about the filler neck of the Ford automobile. This type of

15 filler neck is threaded interiorly for engagement by a cap with the result that any closure whether intended to be ornamental or otherwise necessarily protrudes an appreciable distance above the top of the neck and necessarily appears unsightly. This condition is accentuated by reason of the narrow

20 tapered filler neck of the Ford automobile. Still another difficulty encountered in applying special caps to filler necks of radiators, whether of this or other types, is to insure

25 their retention in the desired predetermined relation to the radiator or other proximate part, when the cap is screwed home. For instance, ornamental caps, as now commonly

30 found on the market, include diametrically extending arms which facilitate retention of the cap and contribute to the ornamental appearance of the cap, but these arms, when the cap is screwed home, must extend transversely of the radiator if the desired effect

35 is to be secured. The difficulty of insuring this position with stock caps applied at random to different cars is obvious.

40 The principal object of the present invention is to eliminate all of the objectionable features of ornamental radiator caps as now found and to provide a cap which will be particularly useful with the type of

45 filler neck found on the radiators of Ford cars. More particularly, the invention seeks to provide an ornamental radiator cap which may be secured in engagement with an interiorly threaded filler neck and yet not protrude to any appreciable extent above the top thereof. Further, the invention has for

50 its object to improve the appearance of filler necks of small diameter by associating with

the radiator cap a skirt whose proportions in length and diameter are pleasing to the eye and which will cover the filler neck in 55 whole or in part when the cap is applied. Still another object of the invention is to associate with an ornamental radiator cap a threaded adapter whose angular relation to the cap may be quickly and conveniently 60 changed in order to change the angular relation which the cap will have to the filler neck when the former is screwed home. A further general object of the invention is to provide an improved ornamental radiator 65 cap which shall be of simple and inexpensive construction, easy of adjustment for proper application to different cars and of a very pleasing appearance. Other incidental objects of the invention will appear 70 at greater length hereinafter in connection with the detailed description of the embodiment of the cap shown in the accompanying drawing, wherein—

75 Figure 1 is a view in plan of a cap embodying the invention, parts being broken away to show the method of engaging the skirt with the body of the cap.

Figure 2 is a view in transverse section through the interiorly threaded filler neck 80 to which the cap of Figure 1 is shown as applied.

While it will be evident to one skilled in the art that some of the improvements to be described particularly hereinafter may 85 find embodiment in a construction in which some of the parts are made as stampings, in the preferred form (illustrated in the drawing), a cap and the threaded adapter therefor are formed as die castings. This 90 fact will account in part for some of the features of design and will indicate to one skilled in the art that any change in the method of manufacture may find corresponding changes in details of design. 95

The body *a* of the cap is cast integral with diametrically extending arms *a'*, the general appearance of the cap conforming to others now known. Heretofore, however, when such caps were made for application to filler necks *b*, such as is illustrated in Figure 2, it was necessary to provide them with a depending annulus threaded exteriorly for engagement with the interior 100

threads b' in the neck. The result of this relationship necessarily was that the body of the cap a was placed entirely above the neck b , thereby presenting an association of parts which was wholly out of proportion. This unsightly condition was further accentuated by reason of the comparatively small diameter of the exposed neck b . One of the principal objects of the present invention is to do away with this condition by providing a construction in which the cap may be threaded well down over the neck and not protrude appreciably above it, and in which, if desired, the neck might be wholly or in part covered by a skirt, such as c , of pleasing proportions as regards length and diameter. To this end, the cap a is cast with an annular recess a^2 in the underside of its body of such diameter as to fit down loosely over the filler neck b of the radiator. The wall of this recess may be cast with an annular groove a^3 to facilitate the convenient and inexpensive attachment to the cap of the skirt c . This attachment is made by placing the skirt c in snug engagement with the wall of the recess a^2 and then stamping dimples c' therein at appropriate intervals for loose engagement with the groove a^3 of the cap. These dimples prevent longitudinal displacement of the skirt c with respect to the cap, but permit free rotative movement therebetween for reasons which will appear later. If it were considered desirable to do so, the skirt c might be omitted, but in the preferred embodiment of the invention which is designed primarily for use on a Ford automobile the most pleasing results in appearance will be secured by attaching a skirt of the character shown to the cap so that the filler neck will be enclosed when the cap is applied.

The improved means for engaging the cap with the interiorly threaded filler neck constitute one of the important features of the invention. Such means comprise an exteriorly threaded adapter d which is of such diameter as to permit it to be engaged with the interiorly threaded neck b . In the preferred form this adapter d is recessed centrally, as at d' , the outline of the recess being irregular, in the illustrated form, octagonal. A boss a^4 of similar outline is cast on the inner face of the cap a and enters the recess d' freely, but with such an engagement as to prevent relative rotation between the adapter d and the cap a . The adapter d may be secured to the cap a by means of a threaded stud e passing centrally through both of the parts, but it is to be understood that other securing means, such as the threaded stem of a motometer or other device or ornamentation might serve the same purpose. This threaded stud e merely prevents axial dis-

placement of the adapter d with respect to the cap a , while the irregularly shaped boss a^4 within the irregularly shaped recess d' prevents relative rotation between the two parts when the cap is threaded on to the neck b .

The effect of the construction described is that the cap may be threaded well down over the neck b and not protrude appreciably above it since the adapted d is threaded down into the neck b and acts as the securing element for the cap. The result is a very ornamental and pleasing effect since the cap is brought into proper relation with the neck. Further, this condition is enhanced by the skirt c which fits down over the neck b either wholly or in part and moves into place when the cap is threaded on. It will be noted in this connection that the filler neck b is tapered and the lower edge of the skirt c may therefore be forced down into snug engagement with this tapered neck, the problem of snug fitting being solved by this relationship. Another result achieved is that if it happens that the arms a' do not lie transversely of the radiator when the adapter d is screwed fully home, that is, when the upper edge of the neck b engages the inner face of the cap, the cap may be immediately removed and the angular relation between the adapter d and the cap changed by backing out the stud e and rotating the adapter d with relation to the cap to a greater or less extent, and then re-engaging the adapter d with the boss a^4 when the parts are in the desired angular relation. The cap is then threaded on to the neck again and it will be found that when the parts are home the arms a' will be brought into the desired relation with respect to the radiator or, at least, that by trying the adjustment described once or twice the exact relation can be obtained. A further advantage of the relation of parts is that with the cap seated on the upper edge of the neck b a watertight union is insured.

As indicated hereinbefore manufacturing considerations may dictate other designs than that shown and variations in proportions, dimensions, materials and arrangement may be made without departing from the spirit of the invention, provided the desired results are secured by means which function in substantially the manner pointed out herein and fall within the language of the appended claims.

I claim as my invention:

1. As an article of manufacture a radiator cap having its body recessed on the inner face to receive the interiorly threaded filler neck of a radiator, an adapter having exterior threads to engage the threads of the filler neck to secure the cap to the neck, means to secure the adapter to the cap, a

skirt extending into the recess and overlying the filler neck, and means to secure the skirt permanently to the cap.

2. A radiator cap having its body recessed 5 on the inner face to receive the interiorly threaded filler neck of a radiator, an adapter having exterior threads to engage the threads of the filler neck, means to secure

the adapter to the cap, and a skirt extending into the recess and secured to the cap, 10 and means to secure the skirt to the cap with capacity for relative rotative movement therebetween.

This specification signed this 14th day of August A. D. 1922.

HENRY YERBURY HOOPER.
